[57] CLAIM

The ornamental design for a physical exerciser, substantially as shown.

DESCRIPTION

FIG. 1 is a front elevational view of a physical exerciser showing my new design;

FIG. 2 is a side elevational view thereof;

FIG. 3 is a top plan view thereof;

FIG. 4 is a bottom plan view thereof;

FIG. 5 is another front elevational view similar to FIG.

1 shown with the chain removed; and

FIG. 6 is another front elevational view similar to FIG. 5 shown with the cushion removed.

Fig. 1.

Fig. 2.

Fig. 3.

Fig. 4.

Fig. 5.

Fig. 6.
